US0D1033419S

(12) **United States Design Patent** (10) **Patent No.:** **US D1,033,419 S**
(45) **Date of Patent:** **** Jul. 2, 2024**

(54) **GAMING DEVICE**

(71) Applicant: **HEWLETT-PACKARD DEVELOPMENT COMPANY, L.P.**,
Spring, TX (US)

(72) Inventors: **Daniel Yoon**, Palo Alto, CA (US); **John William Pennington, Jr.**, Palo Alto, CA (US); **Glenn A. Wong**, Palo Alto, CA (US); **Kevin L. Massaro**, Spring, TX (US); **Marcus Hoggarth**, London (GB); **Stephen De Saulles**, London (GB)

(73) Assignee: **Hewlett-Packard Development Company, L.P.**, Spring, TX (US)

(**) Term: **15 Years**

(21) Appl. No.: **29/813,385**

(22) Filed: **Oct. 28, 2021**

(51) LOC (14) Cl. **14-02**
(52) U.S. Cl.
USPC **D14/314**; D21/332

(58) **Field of Classification Search**

USPC D14/300, 301, 302, 308, 314, 348, 349,

(57) **CLAIM**

The ornamental design for a gaming device, as shown and described.

DESCRIPTION

FIG. 1 is a perspective view of a gaming device showing our new design;

FIG. 2 is a front view of the gaming device of FIG. 1;
FIG. 3 is a rear view of the gaming device of FIG. 1;
FIG. 4 is a left side view of the gaming device of FIG. 1;
FIG. 5 is a right side view of the gaming device of FIG. 1;
FIG. 6 is a top view of the gaming device of FIG. 1; and,
FIG. 7 is a bottom view of the gaming device of FIG. 1.
Broken lines shown in the drawings depict portions of the gaming device that form no part of the claimed design.

1 Claim, 5 Drawing Sheets
